UNITED STATES PATENT OFFICE.

WILMUTH GARY, OF WASHINGTON, DISTRICT OF COLUMBIA.

DESIGN FOR A FLAG, BANNER, PENNANT, SIGN, EMBLEM, OR ARTICLE OF A SIMILAR NATURE.

52,313.

Specification for Design.

Patented Aug. 27, 1918.

Application filed June 6, 1918. Serial No. 238,601. Term of patent 3½ years.

To all whom it may concern:

Be it known that I, WILMUTH GARY, a citizen of the United States, residing at Washington, in the District of Columbia, have invented a new, original, and ornamental Design for Flags, Banners, Pennants, Signs, Emblems, or Articles of a Similar Nature, of which the following is a specification, reference being had to the accompanying drawings, forming a part hereof.

The figure is a plan view of the flag, showing my new design.

The flag as shown on the drawing is of rectangular shape and bears the flags of the allied nations displayed in a circle surrounding a figure consisting of the representation of an eagle perched on a shield.

I claim:

The ornamental design for a flag, banner, pennant, sign, emblem, or article of a similar nature, as shown and described.

WILMUTH GARY.
